TEMPERATURE RESPONSIVE CURRENT
REGULATING MEANS

William C. Sealey, Wauwatosa, Wis., assignor to
Allis-Chalmers Manufacturing Company, Milwaukee, Wis., a corporation of Delaware

Application November 9, 1945, Serial No. 627,725

6 Claims. (Cl. 323—67)

1

This invention relates in general to electrical control systems and relates particularly to control systems in which the controlling elements are susceptible to changes in temperature.

In prior art control systems of the type utilized for controlling the voltage of a circuit, a contact making voltmeter has been utilized to initiate regulating action. Such contact making voltmeter or voltage responsive relay has been connected to measure the regulated voltage, and is balanced against a biasing force when the regulated voltage is at the normal desired value. A contact making voltmeter of this type may be exposed to temperatures which may range from minus forty to sixty degrees centigrade. Such changes in temperature will change the resistance of the coil of a contact making voltmeter, causing more or less force to be applied against the biasing force when the same voltage is applied thereto, so that the contact making voltmeter will not remain in balanced condition when the regulated voltage is at normal desired value.

It is therefore an object of the present invention to provide an improved control system for an electrical current carrying winding, such control system providing compensation for changes in winding resistance due to changes in temperature of the winding.

It is a further object of the present invention to provide an improved temperature compensation control for a voltage responsive winding in which a substantially constant current is maintained when the voltage to which the winding is responsive is at a constant value.

It is a further object of the present invention to provide a temperature compensated voltage responsive winding with further improved temperature compensation actuated by thermal switches exposed to the temperature changes for which the winding is compensated.

It is also an object of the present invention to provide an improved voltage regulating system that is accurate when the controlling elements are exposed to changes in temperature.

Objects and advantages other than those above set forth will be apparent from the following description when read in connection with the accompanying drawing in which:

Fig. 1 is a diagram of connections of a voltage regulating system embodying the present invention;

Fig. 2 illustrates a characteristic curve illustrating the relationship of various factors affecting the control system shown in Fig. 1; and

2

Fig. 3 is a diagram illustrating the use of thermal switches in connection with the resistor in series with the contact making voltmeter of the system of Fig. 1.

The invention is illustrated in the drawing in connection with a voltage regulating system of the type known as a tap changing under load system. An alternating current source of supply 4 is fed through a tap changing device 5 and a series winding 6 of a tap changing transformer having an exciting winding 11, to supply a load circuit 3. A contact making voltmeter or voltage responsive relay 7 has a coil 25 energized responsive to a measure of the regulated voltage in a suitable manner, as by connection to the winding 13.

The contact making voltmeter 7, when unbalanced by a change in the regulated voltage, energizes one or the other windings of a split phase motor 8 from an energizing winding 12 through contacts 9 or 10. The motor 8 runs the tap changing switch 5 in one direction or the other to connect a greater or lesser portion of the winding 6 into the circuit. The winding 6 is connected into the circuit by one or more of the contacts 16 through the contacts of a reversing switch 15 and through a preventive autotransformer 14. The contact making voltmeter 7 is shown in its balanced position in which the magnetic effect of the winding 25 balances the force of gravity acting on the core of the contact making voltmeter 7, or other suitable bias means.

The control system as above described would not be as accurate as desired in some instances, where the coil 25 is subjected to changes in temperature. Outdoor installations of regulators of the type shown may be subjected to temperatures ranging from minus forty degrees centigrade to sixty degrees centigrade. Changes in temperature would change the resistance of coil 25 and therefore a different value of current would balance relay 7 at high temperatures than would balance the relay 7 at low temperatures.

In order to maintain the current in coil 25 at a substantially constant value when the relay 7 is in a balanced condition, independently of changes in ambient temperature, the coil 25 is shunted by a resistor 18 having a high temperature coefficient of resistance and has connected in series therewith a resistor 17 having a low or negative temperature coefficient of resistance.

Thus if the ambient temperature should increase, the resistance of coil 25 and of resistor 18 will increase and the resistance of resistor 17 will remain the same or will decrease. The re-

sistance of resistor 18 will increase more, for a given temperature change than will the resistance of coil 25. Therefore, upon a rise in ambient temperature, the same or a slightly greater value of voltage will be applied to the coil 25 by the coil 13 when the regulated voltage is at the normal desired value. However because of the variation of resistance in the shunt circuit elements, due to temperature change, more current will flow through the coil 25 and less through resistor 18 than would if the ambient temperature was at a lower value.

Conversely, if the ambient temperature drops, the resistance of coil 25 and of resistor 18 will decrease, and the resistance of resistor 17 will remain the same or increase, and the same or less voltage will be applied to the winding 25 by the winding 13 when the regulated voltage is at the normal desired value. However the resistance of resistor 18 will decrease in value more than the resistance of coil 25 and hence a greater portion of the current supplied to the shunt circuit will flow through the resistor 18, thus causing less current to flow through the coil 25. With temperature compensation as above outlined, the relationship between the voltage required to balance the circuit and the ambient temperature is as shown by the curve A—D in Fig. 2.

To further improve the accuracy of the control system, thermally responsive switches 21 and 22 are provided as shown to remove shunts from portions 19 or 20 of the resistor 18 when the ambient temperature has risen to certain predetermined values.

As the ambient temperature rises to a value shown in Fig. 2 as point C, which is shown as 35 degrees centigrade, the thermal switch 21 will open its contact, as shown, thereby removing a shunt around the portion 19 of the resistor 18. Addition of the portion 19 into the circuit shunting the coil 25 permits the available voltage to cause relatively more current to flow through the winding 25 than flows through resistors 18 and 19, so that less voltage is necessary to balance the circuit. As shown in Fig. 2, upon opening of the switch 21, the voltage necessary to balance the circuit drops from about 120.15 volts at point C to 119.8 volts at the point E. As the ambient temperature continues to rise, the voltage necessary to balance the circuit follows the curve EF rather than the curve CD. When the ambient temperature reaches a second predetermined value, shown in the curve of Fig. 2 as fifty degrees centigrade, the thermal switch 22 similarly opens its contact, opening the shunt about the portion 20 of the resistor 18, thereby again dropping the voltage necessary to balance the circuit, as shown in Fig. 2, to the point G.

It is thus seen that with the improved compensation provided by the action of the thermal switches 21, 22, the current in the coil 25 is maintained at a substantially constant value when the regulated voltage is at the normal desired value. The band width in which the relay will remain balanced, extends from 119.7 volts to 120.2 volts or a band width of approximately half a volt. A narrower band width could be obtained by utilization of more thermal switches similar to 21 and 22, adjusted to open their contacts at smaller increments of ambient temperature and utilized in connection with portions of resistor 18 smaller than 19 and 20. If the portion of curve AB is within the desired range of operation, thermal switches such as 21, 22 could be utilized to compensate in this area.

By way of example a satisfactory embodiment of the invention has been utilized in which the thermal switches 21, 22 were set to operate at forty degrees centigrade and fifty degrees centigrade. In this embodiment the resistor 18 was of a high temperature coefficient material, and had a resistance of the order of 500 ohms. The portions 19 and 20 of resistor 18 each had a resistance of the order of 10 ohms. The resistor 17 was made of a substantially zero coefficient of resistance and had a resistance of the order of 400 ohms. The winding 25 had a resistance of the order of 50 ohms. The above example is included in an illustrative rather than a limiting sense.

Although the correction effected by the thermal switches has been illustrated in connection with the shunt resistor 18, such thermal switches could as well act to shunt a portion of the series resistor 17 as shown in Fig. 3. The thermal switches would then operate in the opposite sense, that is, would close their contacts 26 and 27 (when working on the right hand side of the curve of Fig. 2) upon increase in temperature, thereby shunting portions 28 and 29 of resistor 17.

The resistors 18 and 17 are most effective when the temperature coefficients are as above described. The compensation would be effected, with additional thermal switches, if the resistors had positive, negative or zero temperature coefficients of resistance or any combination of such coefficients.

Although but two embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. In a system comprising a source of electric current for supplying current to a conductor having a predetermined temperature coefficient of resistance, the combination of said conductor with means connecting said conductor with said source, and means for reducing the variations of the current in said conductor caused by ambient temperature changes comprising a resistor having a temperature coefficient of resistance which is lower than the temperature coefficient of resistance of said conductor serially connected with said source and said conductor, another resistor connected in shunt with said conductor, and means in addition to the temperature coefficient variation responsive to ambient temperature for varying the effective value of one of the said resistors to thereby vary the voltage drops in said resistors and in said conductor.

2. In a system comprising a source of electric current for supplying current to a conductor having a predetermined temperature coefficient of resistance, the combination of said conductor with means connecting said conductor with said source, and means for reducing the variations of the current in said conductor caused by ambient temperature changes comprising a resistor serially connected with said source and said conductor, another resistor having a temperature coefficient of resistance which is higher than the temperature coefficient of resistance of said conductor connected in shunt with said conductor, and means in addition to the temperature coefficient variation responsive to ambient tempera-

ture for varying the effective value of one of said resistors to thereby vary the voltage drops in said resistors and in said conductor.

3. In a system comprising a source of electric current for supplying current to a conductor having a positive temperature coefficient of resistance, the combination of said conductor with means connecting said conductor with said source, and means for reducing the variations of the current in said conductor caused by ambient temperature changes comprising a resistor serially connected with said source and said conductor, another resistor having a temperature coefficient of resistance which is higher than the temperature coefficient of resistance of said conductor connected in shunt with said conductor, and means in addition to the temperature coefficient variation responsive to ambient temperature for varying the effective value of the said shunt connected resistor to thereby vary the voltage drops in said resistors and in said conductor.

4. In a system comprising a source of electric current for supplying current to a conductor having a positive temperature coefficient of resistance, the combination of said conductor with means connecting said conductor with said source, and means for reducing the variations of the current in said conductor caused by ambient temperature changes comprising a resistor having a temperature coefficient of resistance which is higher than the temperature coefficient of resistance of said conductor connected in shunt with said conductor, another resistor having a temperature coefficient of resistance which is lower than the temperature coefficient of resistance of said conductor connected in series with said source and said conductor, and means in addition to the temperature coefficient variation responsive to ambient temperature for varying the effective value of said shunt connected resistor.

5. In a system comprising a source of electric current for supplying current to a conductor having a positive temperature coefficient of resist-

ance, the combination of said conductor with means connecting said conductor with said source, and means for reducing the variations of the current in the said conductor caused by ambient temperature changes comprising a resistor having a temperature coefficient of resistance which is higher than the temperature coefficient of resistance of said conductor connected in shunt with said conductor, another resistor having a zero temperature coefficient to resistance connected in series with said source and said conductor, and means in addition to the temperature coefficient variation responsive to ambient temperature for varying the effective value of said shunt connected resistor.

5 6. In a system comprising a source of electric current for supplying current to a conductor having a positive temperature coefficient of resistance, the combination of said conductor with 10 means connecting said conductor with said source, and means for reducing the variations of the current in said conductor caused by ambient temperature changes comprising a resistor having a temperature coefficient of resistance which 15 is higher than the temperature coefficient of resistance of said conductor connected in shunt with said conductor, another resistor having a negative temperature coefficient of resistance connected in series with said source and said conductor, and means in addition to the temperature coefficient variation responsive to ambient temperature for varying the effective value of said shunt connected resistor.
